UNITED STATES PATENT OFFICE.

PEDRO ROTH AND MÁXIMO EDUARDO VENTURINO, OF BUENOS AIRES, ARGENTINA.

APPARATUS FOR CONVERTING THE HEAVY PRODUCTS OBTAINED FROM PETROLEUM.

1,208,214.

Specification of Letters Patent.

Patented Dec. 12, 1916.

Application filed October 16, 1916. Serial No. 126,058.

To all whom it may concern:

Be it known that we, PEDRO ROTH and MÁXIMO EDUARDO VENTURINO, citizens of Argentina, residing at No. 750 Moreno street, 5 Buenos Aires, Argentina, have invented certain new and useful Improvements in Apparatus for Converting the Heavy Products Obtained from Petroleum, of which the following is a specification.

- 10 The present invention relates to an apparatus for converting the heavy products obtained from petroleum, into lighter products, a process which forms the subject of an application for Letters Patent Serial No. 126,057 and is therein specified, and an essential object of this invention is an apparatus for carrying out said converting process in a practical manner and on an industrial scale.
- 20 This invention particularly has for its object an apparatus for the industrial conversion of crude petroleum of any description and density, gas oil, mixtures of petroleum by-products with raw petroleum, etc., into lighter products of petroleum.

For brevity and clearness in this specification, the general term "heavy products of petroleum" should be understood as comprising all those hydrocarbons which are 30 heavier than benzin, including kerosene, and the general term "lighter products of petroleum" as including benzin, naphtha, gasolene, and petroleum gases and petroleum ether, that is to say, all light hydrocarbons, commencing with benzin inclusive. The division, however, between heavy and lighter products of petroleum, according to the meaning given to these two terms for the objects of the present invention, should not be 40 considered as being absolute, as on certain occasions as for instance when a more or less large proportion of kerosene is required in the converted product, that hydrocarbon will be regarded as being a light one.

45 According to the converting process above referred to, the heavy petroleum products are caused to fall, either in a liquid condition or atomized, upon a mass of residues of petroleum, asphalt, or oils, heated to a temperature higher than the boiling point of the hydrocarbons which are to be converted, whereupon the vapors and gases generated on the contact of the atomized heavy hydrocarbons with the heated mass are condensed.

In order to perform on an industrial and 55 practical scale the conversion of the crude petroleum, gas oil, mixtures of petroleum by-products with raw petroleum, etc., into petroleum ethers or gases, gasolene, naphtha, benzin, residues and coke, *i. e.*, to eliminate 60 the kerosene and lubricating oils which constitute the larger percentage of the constituents of natural petroleum, it is indispensable:—(a) to extract by ordinary distillation the petroleum ether and gases of petroleum, 65 gasolene, naphtha and benzin which said petroleum may contain; (b) to extract from said petroleum, already deprived of naphtha, the kerosenes and oils which it may contain; 70 (c) to again add these heavier hydrocarbons, kerosenes, gas oil, lubricating oils and paraffins by causing them to fall upon a mass of residues of petroleum, asphalt or oils, heated to a temperature higher than the boiling point of the products so added, and finally, 75 (d) to condense the resulting vapors.

The present invention specially refers to an apparatus combining the conditions necessary to obtain the above results and by means of which such conversion or transformation 80 may be performed in a simple, automatic and continuous manner.

The accompanying drawing is a diagram of a practical form of apparatus for the industrial conversion of heavy petroleum products or by-products into lighter products. 85 Said apparatus consists of a series of converting boilers or stills, arranged on graduated levels and communicating with each other by means of connecting pipes which 90 connect every two successive boilers at about the middle of their height. Each of said boilers or stills is provided, in the manner indicated in the drawings, with pipes or hoses for the discharge of the vapors of distillation generated inside the boiler. In order that the conversion or transformation 95 may take place continuously, it is preferable to arrange a double series of boilers, consisting of two symmetrical halves, of which 100 only one has been illustrated in the drawing.

The boiler or still 1, which, as well as the others of the series, may be of any convenient form or size, is provided with a 105 pipe 3 for the admission of the petroleum and with a pipe or hose 4 for the discharge of the vapors of distillation generated in

the interior of said still. The boiler or still communicates at about the middle of its height, by means of an inclined pipe 5, with another boiler 6, similarly provided 5 with a discharge pipe or hose 7 for the vapors of distillation. The boiler 6 communicates with the boiler 9, arranged at a lower level than the former, through an inclined pipe 8 which connects them at 10 about the middle of their respective heights. The distilling pipe 7 of the boiler 6 ends in a coil 13, arranged within a refrigerating tank 14 wherein a circulation of water or of any other suitable cooling medium is 15 maintained for effecting the condensation of the vapors of distillation which pass to a separating vessel or reservoir, hereinafter to be described. The boiler 9 is provided also with a pipe or hose 10 for the discharge 20 of the vapors of distillation generated in the interior of same and said pipe or hose also ends in a coil 16 arranged within a refrigerating tank, 17, similar in all respects to the refrigerating tank 14. The 25 coil 16, as well as the coil 13, aforementioned, on issuing from the refrigerating tank 17, discharges at the upper part of the separating vessel 15.

The distilling boiler or still 9 communicates with a boiler 12 by means of a pipe 11, at about the middle of their respective heights. This latter boiler 12 is the still in which the conversion is performed. Said converting boiler is provided with a discharge hose 21 for the vapors of distillation, ending in a coil 22 arranged within a refrigerating tank 23 wherein water or any other cooling medium is caused to circulate. Said coil terminates in a trap 25 40 and discharges into a reservoir or vessel 26 in which the condensed converted products are collected. The coil 22 is provided with a pipe 24 which allows of the escape to the outer air of the gases which may 45 not have been condensed by the action of the refrigerating medium in the tank 23.

The separating vessel 15 is provided at the side, near the top, with a discharge pipe 18 which permits of the discharge from 50 said vessel or reservoir of the heavy or middle hydrocarbons which are collected therein after being condensed and separated from the water and other impurities which they may have contained. The pipe 55 18 is arranged with a compressor 19, of any suitable type. The heavy hydrocarbons, after being submitted to the action of said compressor, pass into the interior of the boiler through an atomizer 20.

60 The converting boiler 12 is provided, as are also the other boilers, with a pipe 28 leading from it at about the middle of its height, for the purpose which will be explained when describing the operation of 65 the apparatus.

All the boilers are supported on masonry and at their bases are arranged fire boxes 2, adapted to be heated in any suitable manner, preferably however, by means of oil burners which allow of a better regulation 70 of the temperature. Said stills or boilers are also provided with all necessary fittings, such as thermometers, pressure gages, gage glasses, etc., and with the necessary apertures or doors not shown here, at the foot 75 of the boilers for the purpose of the complete discharge or cleaning when desired.

The other half of the plant, when the same is double, for performing a continuous conversion, will not be described here 80 as it is exactly similar to that already specified.

The separating vessel 15 which forms an essential part of this invention, works automatically. Said vessel consists of a casing 85 provided at the top with a pipe 29 for the escape of the gases, and at one of its sides, near the bottom, with pipe 27 which bends upward and the length of which has been calculated so as to keep the water inside 90 the vessel or reservoir always at the same level. In this manner, when the condensed vapors fall into said vessel through the ends of the coils 13 and 16, they will fill the same above the level of the water, and in the 95 event of any water or impurities being carried along by said vapors, the level of the water in the vessel cannot rise, as it escapes through the pipe 27, as clearly shown in the drawings.

Having now described the arrangement of the apparatus in its entirety as well as the essential parts thereof, we shall proceed to explain its operation for performing the conversion as stated.

In the boiler or still 1 the temperature is maintained at a sufficient height for distilling the light hydrocarbons of the petroleum which is fed into the boiler continuously by means of the pipe 3. Said temperature is about 200 degrees centigrade, which is sufficient for distilling away all the lighter hydrocarbons, down to benzin inclusive. The vapors of distillation issue from said boiler 1 by the pipe 4, and are condensed in any 110 suitable way and led to a convenient reservoir for containing the lighter products of petroleum. When the level in the boiler 1 reaches that of the discharge pipe 5, the petroleum, already deprived of naphtha, 115 passes to the boiler 6 wherein a sufficiently high temperature is maintained for distilling the kerosenes and the proportion of oils which may be desired in this boiler, for example, up to 70 per cent. of the entire 120 volume of petroleum introduced into the boiler or still 1. When the level of the liquid in the boiler 6 reaches that of the discharge pipe 8, it passes into still 9 where 125 said residues will even yet distil off a small 130

quantity of oils and where the temperature should be slightly lower, from 10 to 20 degrees centigrade, approximately. This slight lowering of the temperature is in order to prevent the mass of residues from boiling when these latter enter by the pipe 11 into the converting still 12, after having filled the boiler 9 to the level of the outlet pipe of the latter. The vapors of distillation which escape from the boilers 6 and 9 by the pipes 7 and 10, respectively, are condensed in the coils 13 and 16 and the resulting hydrocarbons, belonging to the heavy products of petroleum in accordance with the present invention, will be collected in the separating vessel 15 which operates in the manner described before and the main object of which is to separate the petroleum or products obtained from the same, from the water or impurities which may have been carried along during distillation and the gases which may not have been condensed. The hydrocarbons contained in the separating vessel 15 pass from it by the pipe 18 to the compressor or pump 19 and finally to the atomizer 20, and from there they are injected into the converting boiler 12 in the form of a fine spray which falls upon the heated mass of residues contained in said boiler; conversion will then take place in the boiler in the manner already described and the vapors of distillation will pass out by the pipe or hose 21 and thence to the coil 22. It will be convenient to keep the temperature within the refrigerating tank 23 exceedingly low, say about 15 degrees centigrade below zero, for the purpose of condensing the petroleum ether which may be carried along by the gases. As has already been stated, the coil is connected to a pipe or trap 25 before its entrance into the vessel 26. The main object of said pipe or trap is to prevent the entrance into said vessel, of the aforesaid gases and petroleum ether, which are allowed to escape to the outer air by the tube 24. After the vapors have been condensed within the coil 22, the resulting liquid passes to the reservoir 26 from which it may be extracted in any suitable manner. These liquids are the converted products which constitute the lighter by-products obtained from the petroleum in accordance with the present invention.

It may happen that on certain occasions among the hydrocarbons gathered in the interior of the reservoir 26, kerosenes and other oils are found, in which case they are submitted to fractional distillation, according to the usual methods and said oils and kerosenes are introduced again into the converting boiler by means of the atomizer 20. For this purpose they may be placed in the separating vessel 15.

When there is some special interest in preserving the kerosenes naturally contained

in the petroleum or even in increasing their proportion, any one of the following two methods may be followed:—

(1) Within the still 1, a temperature should be maintained sufficient to distil, besides the light hydrocarbons, also the kerosene which may be desired; for instance, a temperature up to about 270 degrees centigrade may be employed, and the subsequent procedure followed as indicated in connection with the other boilers. (2) Between the boilers or stills 1 and 6, another boiler, not shown, may be inserted, exclusively destined for distilling off the kerosenes, and the vapors of this distillation will then be collected and condensed separately. As regards the remainder of the operations, the process is the same as that which has been described above.

In order to obtain a continuous conversion, a double series or battery of distilling boilers is used, as before explained, and in the pipes 5 are arranged valves by means of which the operation may be transferred from one side of the double battery or series to the other, in order that the operation of one of the sides may be suspended to allow for effecting the discharge and cleaning of the boilers.

The apparatus which forms the subject of this invention, is evidently susceptible of modification in many ways as regards its arrangement and details of construction, but such modifications are to be considered as being within the limits of the invention, the essential features of which will be clearly defined in the claims hereunto annexed.

We declare that what we claim and desire to secure by Letters Patent, is:—

1. Apparatus for the industrial conversion of the heavy products of petroleum into lighter products, comprising in combination:—a series of boilers arranged in battery, means of connection between every two successive boilers, means for the discharge of the vapors and gases of distillation from each boiler, means for condensing said vapors and gases, means for separating the condensed heavy or middle hydrocarbons from the water and impurities which they may contain, and means for introducing said liquid heavy or middle hydrocarbons into the vapor space of the lowermost or converting boiler and means for condensing the vapors generated within said converting boiler.

2. Apparatus for the industrial conversion of the heavy products of petroleum into lighter products, comprising in combination:—a series of boilers arranged in battery, means of connection between every two successive boilers, means for the discharge of the vapors and gases of distillation from each boiler, means for condensing said vapors and gases, means for separating the

condensed heavy or middle hydrocarbons from the water and impurities which they may contain, means for introducing said liquid heavy or middle hydrocarbons under pressure into the vapor space of the lower-most or converting boiler and a sprayer connected to said last mentioned means through which the middle hydrocarbons are dis-

charged and means for condensing the vapors generated within said converting boiler.

In testimony whereof we affix our signatures.

PEDRO ROTH.
MÁXIMO EDUARDO VENTURINO.
